NONREFILLABLE BOTTLE

Edward J. Morin, Omaha, Nebr.

Application May 19, 1936, Serial No. 80,617

1 Claim. (Cl. 215—32)

This invention relates to a bottle or similar receptacle and it aims to provide a novel means whereby the bottle cannot be refilled except in the face of evidence positively showing that the bottle has theretofore been filled, used, and emptied.

More specifically it is aimed to provide a novel structure wherein the bottle has a supplemental neck adapted to be engaged by a locking cap, which cap and neck are adapted to be fractured or broken off before the contents of the bottle may be emptied, the line of fracture providing evidence of such emptying.

The more specific objects and advantages will become apparent from a consideration of the description following taken in connection with accompanying drawing illustrating an operative embodiment.

In said drawing:—

Figure 1 is a view showing my improvement in substantially central vertical section;

Figure 2 is a view in elevation of the parts of Figure 1, a part of the cap being broken away to disclose details;

Figure 3 is a horizontal sectional view taken on the line 3—3 of Figure 1, and

Figure 4 is an enlarged detail section taken on the same plane as Figure 1.

Referring specifically to the drawing wherein like reference characters designate like or similar parts, 10 designates an ordinary bottle or similar receptacle having a pouring neck as at 11 which is adapted to be closed in any suitable manner as by means of the usual cork or stopper 12.

In accordance with my invention, such bottle 10 which is preferably of glass, has integral with it a supplemental neck 13 surrounding the neck 11 and extending above such neck. The supplemental neck 13 is connected to the neck 11 or body of the bottle by a web 14, much thinner and accordingly much weaker than the necks 11 and 13 and the body of the bottle. In addition, at the junction of the neck 11 and body of the bottle 10, such body is preferably thickened as at 15 to insure fracture of the neck 13 from the bottle, at the web 14 when pressure is applied to the neck 13.

One or more annular ribs or flanges 16 extend outwardly from the neck 13 at spaced locations.

Co-acting with the ribs 16 is a cylindrical cap 17, closed at its upper end and open at its lower end, the latter end having an inwardly extending flange as at 18.

Disposed within the cap 17 is a locking element 19. Such element 19 is initially, for example, a sheet of resilient metal coiled into cylindrical form and permitted to expand, after insertion into the cap 17, into intimate contact with the inner sur-

face of the cylindrical wall of cap 17, abutting the upper end of such cap, and resting on the upper edge or shoulder of the flange 18, the meeting longitudinal edges of such locking member also abutting. Thus the locking member 19 is held in position through its expansive spring action. Prior to insertion of the locking element 19 into the cap, any desired number of locking lugs 20 are struck out angularly therefrom. These lugs may be of any desired shape.

As a result of the invention, a bottle is filled through the neck 11 in the absence of the stopper 12 and the cap 17. After filling, the stopper 12 is positioned as shown in Figure 1, following which cap 17 is forced downwardly over the auxiliary neck 13 with the lugs 20 springing past the ribs 16 and into the spaces between such ribs 16 until the closed upper end of the cap 17 rests on the upper end of the auxiliary neck 13, in which position, removal of the cap is impossible since the lugs are disposed with their points in the spaces between the ribs 16 and engaging the rib above them.

When it is desired to remove the contents of the bottle the cap 17 is rocked or jarred which will be sufficient to sever it from the bottle at the weakened portion or web 14. The fracture at the web will always thereafter be apparent and serve as evidence to future users that the bottle has been emptied of its original contents.

The cap 17 may be made of any desired material, for instance metal or glass.

Various changes may be resorted to provided they fall within the spirit and scope of the invention.

I claim as my invention:—

A device of the class described comprising a bottle having a neck, an auxiliary neck surrounding the first mentioned neck and extending above it, said auxiliary neck being connected to the bottle integrally at the base of the first mentioned neck by a relatively thin web, said auxiliary neck above the web being spaced outwardly from the first mentioned neck, outwardly extending ribs on the auxiliary neck in spaced apart relation, a cap disposed over the auxiliary neck, said cap being closed at its upper end and at its lower end having an inwardly extending flange, a longitudinally split expansive cylindrical locking element within the cap resting on the upper edge of said flange and engaging the upper end of the cap, said locking element having the edges thereof at the split in contact, and resilient lugs extending inwardly from the locking element occupying the spaces beneath the ribs and engaging the under-surfaces of the latter to prevent removal of the cap without fracture of the auxiliary neck at said web.
